UNITED STATES PATENT OFFICE.

EDWARD J. MOORE AND DAVID S. HAWKINS, OF CLEVELAND, OHIO, ASSIGNEES TO
THE FOUNDRY EQUIPMENT COMPANY, OF CLEVELAND, OHIO, A CORPORATION OF
OHIO.

LATHE.

Specification of Letters Patent. Patented Sept. 18, 1917.

1,240,474.

Application filed December 31, 1915. Serial No. 69,543.

To all whom it may concern:

Be it known that we, EDWARD J. MOORE and DAVID S. HAWKINS, citizens of the United States, residing at Cleveland, in the county of Cuyahoga and State of Ohio, have invented a certain new and useful Improvement in Lathes, of which the following is a full, clear, and exact description, reference being had to the accompanying drawings.

10 The object of this invention is to provide a lathe which shall comprise the minimum number of parts, which shall be cheap to manufacture and efficient in service. A feature of our invention is the peculiar arrangement of the motor and a means for adapting the same for driving the lathe in an effective manner. A specific object of the invention is the provision of a simple quickly adjustable and conveniently operable tool rest, 20 forming part of our lathe.

Our invention is hereinafter more fully described in connection with the accompanying drawings, and the essential characteristics are set forth in the claims.

25 In the drawings, Figure 1 is a side elevation of our lathe; Fig. 2 is a plan of the same; Fig. 3 is a vertical longitudinal section through the head of the lathe showing the mounting of the motor and the method 30 of driving the same; Fig. 4 is an end elevation of the head of the lathe; Fig. 5 is a transverse section through the head of the lathe showing the motor and driving wheels; Fig. 6 is a section through the lathe bed 35 showing details of the tool rest; Fig. 7 is a detail plan view of the tool rest showing the rest proper in another position; Fig. 8 is a section through the lathe bed showing the tail stock; Fig. 9 is a detail in axial section 40 of a device for securing work to the live spindle.

Referring to the drawings by reference numerals 10 indicates the bed of the lathe shown as supported at one end on suitable 45 legs 12 and having its other end integral with and supported by an upright head portion 14. As shown, the head portion and legs 12 are each provided with outwardly extending ears or flanges 15 and 16 adapted 50 to receive bolts or screws for securing the lathe in position.

The head 14 comprises substantially a hollow box-shaped upright portion integral with the bed or ways of the lathe and extending upwardly above these ways where 55

suitable bearing portions 17 and 18 are formed which carry bushings 19 in which is journaled the spindle 20. The portions 17 and 18 are separated by an intermediate slot which receives the driving wheel 22 secured 60 on the spindle 20 by suitable screws as indicated at 24. Outside of the bearing portions 18 and 19 the spindle shaft 20 carries collars 25 and 26 secured thereon by suitable screws, and at the end toward the ways the shaft 65 may project toward the collar 25 and be threaded as shown at 28, for receiving a suitable face plate, head center or other work positioning or driving device. Fig. 9 illustrates one simple way of securing the work 70 to the live spindle. This consists of a collar 27 screwed onto the thread 28 and clamping against the end of the spindle a wood screw 29 on which the work may be mounted. This is illustrative of any simple work holding 75 device secured on the thread 28.

As a means for driving the lathe we have provided a suitable electric motor 30 having its shaft 31 projecting beneath the wheel 22 and carrying a driving wheel 33 shown as 80 having a concave surface closely fitting the convex periphery of the wheel 22. The axis of the motor is substantially parallel with the working axis of the lathe, and it is preferably secured in position by a pair of separated ears 35 extending downwardly from the outer end of the motor and embracing the ends of a boss 36, while a pin 37 extends through the ears and the boss, securing the motor thereto in such a manner that it may 85 swing about this pivot. The boss 36 is shown as carried on a rearwardly extending bracket 38 integral with the end wall of the head 14. 90

At the inner end the motor (which is shown as extending through the end wall of 95 the head 14), is provided with a pair of bosses 40 having downwardly opening recesses adapted to receive compression springs 42, the other ends of which are carried in recesses formed in bosses 44 integral with 100 the head 14. It will be noted from Fig. 5 that these springs are so separated as to stand on opposite sides of the center of the motor, and as they tend to press upwardly 105 they may act with equal force to bring the driving wheel 33 into engagement with the wheel 22. The sides of the bosses 40 preferably engage upwardly extending projections 45 integral with the bosses 44. These 110 projections serve to position the motor to

prevent undue lateral strain on the pivot pin 37.

The bed 10 is divided in the usual manner, and the sides thereof extend inwardly to finished surfaces forming the ways 50. The ways proper comprise enlarged portions on inwardly turned flanges of the sides of the bed and are finished on their upper surfaces in a substantially horizontal plane. The inner edges of the ways are preferably finished in vertical planes, the lower sides of the ways presenting surfaces preferably parallel with the upper surfaces of the ways.

The tail stock of the lathe comprises a base portion 55 having horizontal and vertical shoulders fitting the corresponding surfaces of the ways, and from this base portion rise two end members 56 carrying a longitudinal bearing 58 for the dead spindle 60. This member 60 is shown as provided with an integral centering point 62 and the bearing 58 is shown as split at 59 so that by operating a thumb screw 64 the dead spindle may be released and longitudinally adjusted with relation to the tail stock by means of its threaded engagement therewith and again clamp in any desired position. To clamp the tail stock in any position to which it may have been adjusted longitudinally of the ways we have provided a screw 65 having a non-circular head 66 standing between the end members 56 and extending downwardly through a clamp member 67. This clamp has shoulders engaging the under and inner surface of the ways (as shown in Fig. 8), while a hand operated nut 68 may securely clamp the tail stock in any desired position on the ways by drawing the members 65 and 67 together in the usual manner.

The tool rest comprises a base member 70 shown as substantially circular and adapted to rest on the upper surface of the ways and having a downwardly extending substantially circular boss fitting between the inner vertical surfaces of the ways and carrying an outstanding arm 73 which is provided with a boss 74 having a vertical opening 75 adapted to receive a cylindrical lug or shank 76 of the tool rest proper 77. This tool rest is shown as having a wedge-shaped edge 78 formed integral with the body of the tool rest, and preferably standing substantially at the level of the axis of the spindles. Above the shank 76 is formed a recess having a threaded lower end receiving a hand operated nut 80, for clamping the tool rest in any desired position with relation to the arm 73. The body of the tool rest, which is rotatable on the bed, is clamped in position by a screw 82 having its head seating in a suitable recess in the base portion 70 and extending downwardly to a clamp 84 similar to the clamp 67 and receiving at

its lower threaded end a hand operated nut 85 similar to the nut 68.

It will be seen from the foregoing description of the tool rest that we have provided a tool rest which may be adjusted in any desired position. As stated the wedge shaped edge stands substantially at the height of the centers, and accordingly the tool rest may be used while standing either parallel with the axis of the spindles or at right angles thereto, as when working in front of a face plate, or when turning a disk, or this wedge-shaped edge may be positioned at any intervening angle. The tool rest may be readily adjusted for these various positions by releasing the nut 85 permitting the arm 73 to be swung around the screw 82 and the desired angle of the supporting edge with relation to the arm 73 may be obtained by operating the nut 80. We have found in practice that this tool rest is not only simple and efficient but the operator may very quickly adjust the same by operating the nut 80 with one hand while operating the nut 85 with the other. The tool rest may be quickly brought to the desired position and there clamped by simultaneously tightening both the nuts 80 and 85.

From the foregoing description it will be seen that we have provided a very simple yet practical and durable lathe. The manner of driving the lathe has many advantages. The driving mechanism may, first, be cheaply manufactured, and, second, it is very efficient in operation. Comparatively small motors such as we prefer to use, may be run at a very high speed, and the relative sizes of the wheels 33 and 22 may be such as to obtain the maximum power commensurate with the speed of the lathe and the work to be done. The parts are durable and are not liable to get out of order. The springs 42 which serve to hold the driving wheels together have the additional advantage of so supporting the motor that it is very silent in operation which is obviously a desirable characteristic.

Having thus described our invention what we claim is:

1. In a lathe, the combination with a frame having a hollow standard, of a live spindle, a wheel thereon extending into said standard, and a pivotally mounted motor having a pulley within the standard yieldingly bearing against said wheel.
2. In a lathe, the combination with a frame, of a live spindle journaled therein, a wheel on said spindle, an extension on the frame, a motor pivoted to said extension having its armature shaft extending beneath said wheel, a pulley on the armature shaft engaging the wheel, and means pressing the motor upwardly to cause a yielding engagement between the pulley and wheel.

3. In a lathe, the combination with a frame having a hollow standard, a live spindle journaled in the frame at two points, a wheel secured to the spindle between its 5 bearings and depending into the hollow of the frame, said frame having an extension, a motor pivoted to the extension and extending into the hollow of the frame, a pulley on the armature shaft of the motor 10 engaging the under side of said wheel, and a spring pressing upwardly on the motor frame between its pivot and the pulley.
4. In a lathe, the combination of a hollow head standard, a bed extending from the 15 standard in one direction, a bracket extending from the standard in the opposite direction, a motor hinged near its outer end on a horizontal pivot to the outer end of the bracket, said motor extending into the hollow of the standard, a spring between the 20 inner end of the motor and standard tending to raise the motor, a live spindle journaled in the upper portion of the standard, a vertical wheel on said standard, and a pulley on 25 the armature of said motor engaging said wheel.
5. In a lathe, the combination with a frame having a bed, of a live spindle, a 30 motor pivoted to the bed and having a pulley on its armature shaft adapted to engage said driving wheel, the motor frame having two downwardly extending recessed lugs, and a pair of com-
- pression springs entering the recesses of said lugs and coöperating recesses in the standard to yieldingly press the motor upwardly to cause the pulley to frictionally engage the wheel. 35
6. In a lathe, the combination of a bed having a longitudinal opening providing 40 ways, an arm having a portion adapted to rest on the top of said ways and a downwardly extending round boss adapted to substantially engage the inner faces of the 45 ways and prevent lateral shifting of the arm, means for clamping the arm in place, and a tool rest pivotally carried by the arm.
7. In a lathe, the combination with a bed having an opening providing ways, an arm having a substantially circular portion 50 adapted to rest on top of said ways and having a downwardly extending substantially cylindrical boss extending between the ways and having a diameter substantially equal to the distance between the ways, a 55 piece bridging the ways on the under side, a bolt connecting the arm and piece and equipped with a nut for clamping such parts together, a tool rest connected with the arm on a vertical pivot, and means for clamping 60 such pivot.

In testimony whereof, we hereunto affix our signatures.

EDWARD J. MOORE.
DAVID S. HAWKINS.
